PILLOW AND APPLIANCE THEREFOR

Edward J. Barcalo, Buffalo, N. Y., assignor to
Six-Way Corporation, Buffalo, N. Y., a corpora-
tion of New York

Application March 9, 1933. Serial No. 660,125

9 Claims. (Cl. 45—57)

This invention relates to stuffed or relatively soft, pliable pillows or cushions such as may be used on beds or couches, and also to means adapting them to support books, magazines and the like in convenient reading positions. More particularly, the invention relates to improvements in pillows of the sort disclosed in my pending U. S. application for patent, Serial No. 642,091, filed November 10, 1932, and further to a device or attachment engageable with such a pillow to provide thereon a projecting shelf or ledge adapted to support, on a face of the pillow, a book or other article in suitable position for reading or examining the book or article.

15 The pillow disclosed in said pending application is a stuffed or more or less yielding, pliable or resilient pillow comprising a case of textile or other suitable flexible sheet material stuffed with a filling of relatively soft and compressible 20 or resilient material such as kapoc, cotton, hair, feathers or the like commonly used as fillings for pillows and cushions. Said pillow may be of triangular or other suitable shape in cross section, having side faces which are disposed 25 at an angle to each other and are of such proportions that the pillow may rest stably on one or another of said side faces as a base, with another of said side faces extending at an angle or inclination to the base. Furthermore, the 30 side faces of said pillow are arranged at such angularity to each other that by placing the pillow on one side face, another of said side faces will slope at one angle to the base, whereas if the pillow is placed on a different side face 35 as a base, another face of the pillow will slope at a different angle to the base. Thus, the pillow is adapted to be used in different positions to provide a comfortable, yielding support for the head or other portion of the user when resting in different postures. Said pillow is also provided with means for supporting a book, magazine or other article on one or another of the side faces of the pillow, means of different 40 constructions for this purpose being disclosed in said application. One such means comprises a bar which is removably retained on the pillow so as to form a book or article-supporting ledge or shelf extending lengthwise of and projecting outwardly from a face of the pillow.

50 One object of the present invention is to provide a pillow of the character mentioned with a supporting shelf or attachment of novel and desirable construction adapted to be readily applied to and removed from the pillow. Other 55 objects are to provide an attachment adapted

to be readily applied to pillows of the character mentioned to adapt them to support books or other articles; also to provide a book-supporting shelf or attachment of novel construction adapting it to be removably retained in operative position on such a pillow without making the pillow with engaging or retaining devices or parts for the attachment which deface or detract from the ornamental appearance of the pillow or which might be objectionable in the use of the pillow 60 when the attachment is removed; also to provide an article rest, shelf or attachment which is adapted to be readily secured in operative position on the pillow and which, when removed from the pillow, can be folded into compact 65 form; and also to provide pillows of the type mentioned and book rests or attachments therefor having the other features of improvement and advantage hereinafter described and set forth in the claims.

70 In the accompanying drawing:

Fig. 1 is a perspective view of a pillow and book rest shelf, or attachment therefor, embodying my invention.

Fig. 2 is a perspective view of the shelf or 80 attachment and showing a different position of the same on a pillow represented by broken lines.

Fig. 3 is an end view of the pillow with the shelf or attachment applied thereto.

Fig. 4 is a similar end view but showing a different position of the pillow and of the shelf or attachment.

Fig. 5 is a plan view of the shelf or attachment detached from the pillow and folded.

The pillow as illustrated in the drawing is of substantially triangular shape in cross section having opposite ends 10 of substantially triangular shape, and three substantially rectangular side faces 11, 12 and 13. As shown, each end has 95 three unequal sides or edges and three unequal angles, one angle being a substantially right or slightly obtuse angle and the other two angles unequal acute angles. The three side faces 11, 12 and 13 of the pillow are, therefore, of different 100 widths but each side face is preferably of sufficient width to provide a base of substantial proportions on which the pillow may rest stably as a base. The pillow may be of other suitable shape.

It is not necessary to further describe herein 105 the construction of the pillow. It may be constructed as fully described in said application, to which reference may be had for a more detailed description. However, it may be noted that the pillow is provided at its opposite ends, inwardly 110

from the edges thereof, or at the central portions of the ends, with projections or parts 14 adapted for the engagement of the attaching members of the book shelf or attachment. These parts 5 14, as disclosed in said application, may be buttons attached to and forming the securing means for a stay or tie 15 which extends lengthwise through the pillow and connects the end walls of the case for limiting the extent to which they 10 can bulge outwardly under pressure or weight on the pillow, this stay or tie preferably being adjustable so that it can be lengthened or shortened to make the pillow firmer or softer, as may be desired. The buttons thus connected provide 15 headed projections on the opposite ends of the pillow with which the attaching arms or parts of the book shelf or attachment can be readily engaged for securing the attachment on the pillow.

20 Said shelf or attachment, as shown, comprises a thin metal bar or strip 16 and attaching arms 17 hinged to the opposite ends of the bar 16 so that the arms can swing outwardly and inwardly away from and toward the bar. The arms are provided at their outer ends with loops or hooks 18, and when the arms are swung outwardly so as to extend laterally from the bar 16, the hooks or loops 18 are adapted to be hooked over or engaged with the projections or fastenings of the buttons 14. 25 30 When so engaged with the projections, the shelf or bar 16 will be held against one face of the pillow with the two arms straddling the pillow or extending inwardly from the bar at the ends of the pillow. The bar 16 may be stiffened by forming it with a longitudinal bead or corrugation 19, which formation enables the bar to be made of a thin, light strip of metal and, nevertheless, it will be substantially rigid in use and remain straight under the weight of a book or article 35 40 thereon.

45 Preferably the hinges connecting the arms 17 to the bar 16 are arranged with their axes extending at opposite inclinations to the direction of the length of the bar, as clearly shown in Fig. 5, so that when the arms are folded inwardly, they may lie lengthwise flat against and substantially parallel with the bar 16, and when the arms are swung outwardly and engaged with the projections 15 on the ends of the pillow, they will position the 50 bar 16 so that it will project outwardly substantially perpendicularly from the face of the pillow against which it bears and is held by the arms. Each of the arms 17 is conveniently made from a 55 stiff wire having one end bent at an obtuse angle to its main portion and retained in a loop or bent-over end 20 of the bar 16 to form the hinge joint between the arm and the bar.

60 As shown in Fig. 1, the pillow may rest on its widest side or face 11 sloping upwardly, and with the shelf or bar 16 bearing against the face 11 near its lower edge and extending substantially parallel therewith. If desired, the pillow can be placed on its narrowest side or face 13, as shown 65 in Fig. 4, with the face 11 extending upwardly at a steeper slope and with the bar or shelf 16 bearing against the inclined face 11 near its then lower portion. Thus, by these different positions, the pillow is adapted to support a book at different inclinations, as may be most suitable for 70 reading by the person using the pillow. Similarly, the pillow can be arranged to support the book or other article on one of its other side faces. For example, as indicated in Fig. 2, the pillow 75 rests on its widest side 11, with the bar or shelf

80 arranged to support a book or article on the face 12 of intermediate width, and this holds the book at still another inclination. Since the pillow is relatively pliable or compressible, it can be more or less deformed or distorted by pressure so as to vary somewhat the inclination of the book in each of its possible different positions on the pillow, thereby adapting the device to the needs of different readers when held on their laps or otherwise supported.

85

85 The shelf or attachment can be readily removed from the pillow by disengaging the hooked ends of its arms from the engaging buttons or parts on the ends of the pillow, and when so removed, the arms can be folded flat against the bar 16, shown in Fig. 5. When the attachment is removed from the pillow, the pillow can be used like the pillow of my U. S. Patent No. 1,890,358, issued Dec. 6, 1932, to provide a comfortable support for the head or other part of the body of the user in 90 different desired postures, depending upon the position in which the pillow is placed, and when so used, there are no parts or projections on the pillow which might detract from its appearance or which, by reason of their location, might make 95 the pillow uncomfortable or objectionable in use as a head or body rest. The attaching buttons or parts 15 at the ends of the pillow are not objectionable in these respects; in fact, they are, in practice, made of pleasing appearance and add 100 105 an ornamental finish to the pillow.

95

I claim:

1. A relatively pliable pillow having a face on which the pillow may rest as a base, and a face extending at an angle to said base, and a shelf 110 having means releasably engageable with parts on the opposite end faces of the pillow for removably retaining said shelf in position to support an article on said angularly extending face.

2. A relatively pliable pillow having a face on 115 which the pillow may rest as a base, and a face above said base, and a shelf having means releasably engageable with parts on the opposite end faces of the pillow for removably retaining said shelf in position to support an article on 120 said last mentioned face.

3. A relatively pliable pillow having a face on 125 which the pillow may rest as a base, and a face above said base, and a shelf having foldable arms engageable with parts on the pillow for removably retaining said shelf in position to support an article on said last mentioned face, said arms being foldable to positions substantially lengthwise of said shelf when the latter is removed from the pillow.

130 4. A relatively pliable pillow having a face on which the pillow may rest as a base, and a face extending at an angle to said base, and having parts at the central portions of its opposite ends for the engagement of shelf-attaching arms, and a shelf having arms at its ends releasably engageable with said parts on the ends of the pillow for removably retaining said shelf in position to support an article on said angularly extending face.

135 5. A relatively pliable pillow having side faces on one of which the pillow may rest as a base with another of said faces extending at an angle to said base, and a shelf having arms at its ends arranged to straddle the pillow and releasably engageable with parts at the opposite ends of the pillow for removably retaining said shelf in position extending lengthwise against a side face of the pillow.

140 6. A relatively pliable pillow having faces on 145

- one of which the pillow may rest as a base with another face extending at an angle to the base, and a bar having arms hinged at its ends and engageable with parts on the pillow for retaining 80
 5 said bar on said pillow in position to form a ledge projecting out from said angularly extending face, said arms being foldable to lie lengthwise against said bar.
7. A bar having arms hinged at its opposite 85
 10 ends to swing to and from positions in which the arms extend laterally from the bar, the outer ends of said arms being engageable with a pillow for retaining the bar on the pillow in position to form a ledge projecting out from a face of the 85
 15 pillow.
8. A bar having arms hinged at its opposite 90
 20 ends to swing to and from positions in which the arms extend laterally from the bar, the outer ends of said arms having hooks engageable with parts on a pillow for retaining the bar on the 90
 25 pillow in position to form a ledge projecting out from a face of the pillow.
9. A bar having arms hinged at its opposite 95
 30 ends to swing to and from positions in which the arms extend laterally from the bar, the outer ends of said arms having hooks engageable with parts on a pillow for retaining the bar on the 95
 35 pillow in position to form a ledge projecting out from a face of the pillow.
10. A bar having arms hinged at its opposite 100
 40 ends to swing to and from positions in which the arms extend laterally from the bar, the outer ends of said arms having hooks engageable with parts on a pillow for retaining the bar on the 100
 45 pillow in position to form a ledge projecting out from a face of the pillow.
11. A bar having arms hinged at its opposite 105
 50 ends to swing to and from positions in which the arms extend laterally from the bar, the outer ends of said arms having hooks engageable with parts on a pillow for retaining the bar on the 105
 55 pillow in position to form a ledge projecting out from a face of the pillow.
12. A bar having arms hinged at its opposite 110
 60 ends to swing to and from positions in which the arms extend laterally from the bar, the outer ends of said arms having hooks engageable with parts on a pillow for retaining the bar on the 110
 65 pillow in position to form a ledge projecting out from a face of the pillow.
13. A bar having arms hinged at its opposite 115
 70 ends to swing to and from positions in which the arms extend laterally from the bar, the outer ends of said arms having hooks engageable with parts on a pillow for retaining the bar on the 115
 75 pillow in position to form a ledge projecting out from a face of the pillow.
14. A bar having arms hinged at its opposite 120
 80 ends to swing to and from positions in which the arms extend laterally from the bar, the outer ends of said arms having hooks engageable with parts on a pillow for retaining the bar on the 120
 85 pillow in position to form a ledge projecting out from a face of the pillow.
15. A bar having arms hinged at its opposite 125
 90 ends to swing to and from positions in which the arms extend laterally from the bar, the outer ends of said arms having hooks engageable with parts on a pillow for retaining the bar on the 125
 95 pillow in position to form a ledge projecting out from a face of the pillow.
16. A bar having arms hinged at its opposite 130
 100 ends to swing to and from positions in which the arms extend laterally from the bar, the outer ends of said arms having hooks engageable with parts on a pillow for retaining the bar on the 130
 105 pillow in position to form a ledge projecting out from a face of the pillow.
17. A bar having arms hinged at its opposite 135
 110 ends to swing to and from positions in which the arms extend laterally from the bar, the outer ends of said arms having hooks engageable with parts on a pillow for retaining the bar on the 135
 115 pillow in position to form a ledge projecting out from a face of the pillow.
18. A bar having arms hinged at its opposite 140
 120 ends to swing to and from positions in which the arms extend laterally from the bar, the outer ends of said arms having hooks engageable with parts on a pillow for retaining the bar on the 140
 125 pillow in position to form a ledge projecting out from a face of the pillow.
19. A bar having arms hinged at its opposite 145
 130 ends to swing to and from positions in which the arms extend laterally from the bar, the outer ends of said arms having hooks engageable with parts on a pillow for retaining the bar on the 145
 135 pillow in position to form a ledge projecting out from a face of the pillow.
20. A bar having arms hinged at its opposite 150
 135 ends to swing to and from positions in which the arms extend laterally from the bar, the outer ends of said arms having hooks engageable with parts on a pillow for retaining the bar on the 150
 140 pillow in position to form a ledge projecting out from a face of the pillow.

EDWARD J. BARCALO.
